INVENTOR:

William E. Keach.

UNITED STATES PATENT OFFICE.

WILLIAM E. KEACH, OF FITCHBURG, MASSACHUSETTS.

CLEARER FOR DRAWING-ROLLS.

SPECIFICATION forming part of Letters Patent No. 658,918, dated October 2, 1900.

Application filed August 4, 1899. Serial No. 726,124. (No model.)

To all whom it may concern:

Be it known that I, WILLIAM E. KEACH, a citizen of the United States, residing at Fitchburg, in the county of Worcester and State of Massachusetts, have invented a new and useful Improvement in Clearers for Drawing-Rolls, of which the following is a full, clear, and exact description, reference being had to the accompanying drawings, forming a part 10 of this specification, in explaining its nature.

The invention relates to the herein-described clearers for drawing-rolls of drawing-frames.

The invention will be described in connection with the drawings, wherein—

Figure 1 is a view, partly in elevation and partly in vertical section, of a drawing-frame equipped with my invention; and Fig. 2 is a view in perspective of the clearer for the top 20 rolls removed and inverted.

Referring to the drawings, A A' A² represent the upper or top rolls of the drawing-frame, and B B' B² the underneath or lower rolls of such frame. The roving passes 25 through the machine from the rolls A B, and the rolls remove from it more or less fiber or lint and which it is the purpose of my invention to immediately remove and in such a way as to hold it from dropping back upon 30 the roving.

The invention further relates to the construction of the clearers, whereby they are made to fit without adjustment-rolls, which may be adjustable in relation to each other or 35 otherwise occupy different relations to each other.

The invention further relates to the peculiar construction of the clearers, whereby an economy in the manufacture is obtained.

40 C represents the clearer used with the upper rolls; C', the clearer used with the lower rolls. Each clearer preferably is made of one piece of wood. The upper clearer C has the section c, having the plane or level under surface c', extending from the corner c² to the corner c³. It is covered with the clearer-cloth c⁴, which is united thereto by cement or in any other desired way and which provides a clearing-surface which extends in front of 45 a vertical line drawn diametrically through the roll A' and considerably behind a diametrical line drawn vertically through the

roll A. The extent of these overlaps is sufficient to accommodate the same clearer to any usual variation in the position of the rolls A 55 A' with respect to each other, also with respect to the roll A²—that is, within certain limits. To cover the entire range of drawing-machines, only two sizes of the clearer would probably be necessary. The upper 60 clearer C has also formed lengthwise it in front of the corner c² and between it and the corner c⁵ a deep longitudinal channel or cavity c⁶, which is adapted to receive the lint or fiber removed from the roll A². From the 65 corner c⁵, which is arranged upon the line of the vertical diameter of the roll A², the clearer C extends downward to form a nose c⁷, the inner surface c⁸ of which is curved to be parallel with the curve of the surface of the roll 70 A², and this surface is lined with clearer-cloth c⁹ from the corner c⁵ of the clearer to the corner c¹⁰, and it is held in contact with the surface of the roll A² throughout its extent. This and the roll B², being the last rolls 75 to act upon the roving, are the ones from which it is especially hard and desirable to remove the lint or fiber, and for this reason the clearer is arranged to bear upon a larger area or surface of the roll. It is also desirable that the lint or fiber removed from the roll should not drop back upon the roll or upon the roving, and for this purpose the rear end of the clearer-section c⁹ is not carried back of a vertical line passing through 80 the center of the roll. By ending this section of the clearer at this point and by providing an upward-extending cavity beyond it space is formed for receiving and holding the lint or fiber above the roll A² and removed from the roll A', and the lint or fiber 85 is forced and held therein in such a manner as to stay there and have no tendency to drop between the rolls upon the roving. The clearer C is held in place by pins D, projecting from the ends of the clearer and held by the clearer, which pins enter vertical slots d in the downward extensions d' from the cover d². The slots prevent horizontal movement of the clearer, but permit it to have a slight 90 vertical movement with respect to the roving. The weight of the clearer is generally sufficient to maintain a working relation between its clearing-surfaces and the rolls.

Usually an upper clearer is made of a length to cover two pairs of rolls. The lower clearer C' is of the same length as the upper clearer, is arranged beneath the under rolls B' B², 5 preferably does not extend beneath the roll B, is supported by the frame E', and has the section f, which is plane, and the upwardly-curved end f'. The sections f f' are integral, and the section f extends considerably beyond 10 a vertical line drawn through the center of the roll B'. The section f' has a curved surface f² in continuation of the plane surface of the section f, and both surfaces are covered with clearer-cloth f³. The clearer is 15 adapted to be moved horizontally upon the frame E' and is held in contact with the rolls B² B' by means of the drawing-cord f⁴, which is attached to the rear end of the clearer and which extends about the rolls B' B² in their 20 reduced parts and the weight f⁵ attached to the outer end of said drawing-cord.

By making the rear end of the clearer to overlap the roll B' the same clearer will serve without adjustment for different positions of 25 the drawing-rolls B' B² in the same frame or in different frames.

It will be understood that the rolls A' B' are revolved more rapidly than the rolls A B and the rolls A² B² more rapidly than the rolls 30 A' B', and that the more rapidly the rolls are turned the more likely they are to pick up lint or fiber and finally catch the roving or thread. For instance, the roll A revolves so slowly that it collects but very little, if any, 35 and can do without a clearer; but I prefer to use one therewith to remove what little may collect thereon and also that the roll may act as a support for the entire body of the clearer. The rolls A' B' revolve sufficiently fast to 40 pick up or attract some fiber or lint, and the rolls A² B² revolve so rapidly that they take on lint or fiber very quickly, and for this reason it is essential that the area of the clearer-surface upon the roll should be large— 45 about one-quarter of the entire area of the roll—and it is also desirable for this reason that the clearers begin to act upon the surfaces of the rolls where they do—that is, at lines in extension of the horizontal diameters 50 of the rolls—and that the upper roll delivers bunches of fiber or lint upon a vertical line extending through the center of the roll, this length of bearing and the position of delivery acting to remove the fiber and dust from the 55 roll into the cavity provided for it, where it is held in a somewhat matted shape, thus doing away with the possibility of the roll dragging it downward onto the roving and

cause overlapping with it and the other fiber or lint upon the roll.

60

I would say that the invention is applicable to all classes of machines using drawing-rolls in the treatment of any kind of fiber, and I would further say that the devices as made fit without change machines of different makers and of different types and also different adjustments of the rolls of such machines.

65

Having thus fully described my invention, I claim and desire to secure by Letters Patent 70 of the United States—

1. A clearer for drawing-frames comprising a single integral piece of material, having upon its working face a curved and a flat clearing-surface separated by a lint receiving 75 and retaining space extending from a point substantially above the front drawing-roll to the second drawing-roll, the clearing-surface of the curved face being in contact throughout with the drawing-roll and being carried 80 only to the corner of the lint receiving and retaining space between the front and second drawing-rolls, whereby lint cleared from the drawing-roll is carried at once free of the clearing-surface into the lint receiving and 85 retaining space.

2. A clearer for a series of sets of drawing-rolls of a drawing-frame comprising a long, flat, relatively-wide, integral support, common to all the series and sets, and providing 90 a series of sets of independent faces or beds for receiving and holding clearer-cloth and presenting it to said series of sets of drawing-rolls, which sets of independent faces or beds are separated from each other by cross-recesses, each of which sets of faces or beds having a relatively-wide, flat surface and a curved surface, clearer-cloth applied to said flat and said curved surfaces, the latter contacting throughout its extent with the drawing-roll, the said flat and curved surfaces being disposed with respect to each other to provide means for the simultaneous setting of the clearer to a series of sets of drawing-rolls and, also, to provide means whereby the 95 same clearer may be applied to drawing-frames in which the sets of drawing-rolls vary in setting or distance from each other and the said curved and flat surfaces being adapted to bear upon the surfaces of the rolls in 100 the manner indicated, as and for the purposes set forth.

WILLIAM E. KEACH.
